LOOPER MECHANISM FOR SEWING MACHINES

Filed Nov. 24, 1922

6 Sheets-Sheet 4

A technical line drawing of a mechanical assembly, possibly a valve or pump component. The drawing shows a central vertical rod (5) with a handle (4) at the top. A circular base (23) is at the bottom. Various parts are labeled with numbers: 10, 13, 12, 11, 29, 16, 14, 18, 25, 20, 19, 24, 17, 21, and 22. The drawing uses hatching and cross-hatching to differentiate parts. Handwritten text 'FIG. 6.' is written across the top left of the drawing.

This technical drawing illustrates a mechanical assembly, possibly a gear mechanism. The drawing is labeled 'FIG. 7.' in the top left corner. The assembly features a central housing with various internal parts and a shaft extending to the right. Numerous components are numbered, including:

- 10: A top plate or cover.
- 11: A small part near the top center.
- 12: A part positioned above and to the left of 10.
- 13: A part positioned below and to the left of 10.
- 14: A part positioned above and to the right of 10.
- 15: A part positioned below and to the right of 10.
- 16: A part positioned below 14.
- 17: A part positioned to the left of 10.
- 18: A part positioned below 17.
- 19: A part positioned to the left of 18.
- 20: A part positioned below 18.
- 21: A part positioned below 19.
- 22: A long, thin shaft extending from the right side.
- 23: A part positioned at the bottom center.
- 24: A part positioned below 23.
- 25: A part positioned to the right of 22.
- 26: A part positioned to the left of 22.
- 27: A part positioned to the left of 26.
- 28: A part positioned to the right of 26.
- 29: A part positioned to the right of 27.

A technical line drawing of a mechanical assembly, possibly a clutch or gear mechanism. The drawing shows a central housing with various parts labeled with numbers. Key components include a flywheel at the bottom (labeled 21), a main shaft (labeled 22), a gear assembly (labeled 23, 24, 25, 26, 27, 28, 29), and a bearing housing (labeled 10, 11, 12, 13, 14, 15, 16, 17, 18, 19, 20). The assembly is shown in an exploded or partially assembled state, with some parts shown in cross-section.

LOOPER MECHANISM FOR SEWING MACHINES

Application filed November 24, 1922. Serial No. 602,990.

The invention relates to new and useful improvements in looper mechanisms for sewing machines, and more particularly to a mechanism for oscillating the thread carrying looper and giving a dwell thereto at the forward end of its stroke, or while the looper is in the needle thread loop.

An object of the invention is to provide a looper operating mechanism of the above type, wherein the looper is given an extended dwell substantially during the entire period that the needle is above the work support, and wherein the looper is moved very quickly into and out of the needle loop so that the stroke of the looper does not have to be unduly shortened.

A further object of the invention is to provide a looper operating mechanism of the above type wherein the looper carrier is provided with a radially extending arm, and a sleeve slidably mounted on said arm is also caused to travel in a curved path so as to impart oscillations to the looper and give an extended dwell thereto while said looper is in the needle thread loop.

A still further object of the invention is to provide a looper operating mechanism of the above type wherein the means which moves the sleeve back and forth is mounted on the looper support which carries the looper and is oscillated with said looper support when the looper is moved laterally to avoid the needle.

These and other objects will in part be obvious and will in part be hereinafter more fully disclosed.

In the drawings which show by way of illustration one embodiment of the invention—

40 Figure 1 is a front view of a portion of a machine with the cloth plate removed, embodying the invention;

Fig. 2 is an end view of the same;

45 Fig. 3 is a plan view of the looper operating mechanism with the looper at the rear end of its stroke;

Fig. 4 is a similar view but with the looper at the forward end of its stroke and at the beginning of its dwell in the needle loop;

50 Fig. 5 is a similar view but showing the

sleeve as moved to the extreme outer position on the looper oscillating arm;

Fig. 6 is a side view of the parts positioned as in Fig. 3;

Fig. 7 is a side view of the parts positioned as in Fig. 4;

Fig. 8 is a side view of the parts positioned as in Fig. 5;

Fig. 9 is a diagrammatic view showing the movements of the looper into and out of the needle loop;

Fig. 10 is a view partly in section and partly in end elevation, showing the looper carrier as moved laterally to give the looper a needle avoiding movement;

Fig. 11 is a horizontal sectional view showing the upper loop forming mechanism with the parts as positioned when the needles are at the lower ends of their strokes;

Fig. 12 is a similar view but showing the loop forming members in engagement with the left hand needle thread, and the loop partially formed therein;

Fig. 13 is a view similar to Fig. 12 but showing the loop as completely formed and held for the right hand needle, and

Fig. 14 is a view showing in plan the work support and the devices for guiding the material for stitching the sweat band of a hat.

The invention is directed primarily to a looper operating means for moving a thread carrying looper into and out of a needle thread loop. The looper operating mechanism is particularly adapted for operating a looper which cooperates with two needles arranged abreast. The looper operating mechanism is also especially adapted for stitching a sweat band and has been so illustrated in the drawings. In the stitching of a sweat band by a two-needle machine, it is desirable to carry the loop of the inner or left hand needle thread above the material over into the path of the needle which passes outside of the material so as to form a covering stitch. I have provided a new form of loop forming mechanism which I prefer to use when my improved looper operating mechanism is used for forming covering stitches. The looper operating

mechanism consists of a pivoted carrier on which the threaded looper is mounted, a looper support on which the carrier is pivoted, and which looper support is moved 5 for giving to the looper a needle avoiding movement. Projecting radially from the looper carrier is an arm on which is mounted a sleeve. This sleeve is carried by a lever also pivotally mounted on the looper support 10 and moving therewith when the looper is given its lateral movement. This lever is so disposed that the sleeve which is pivoted thereto moves in a curved path from a position where the sleeve slides horizontally or 15 substantially so on the radial arm, to a position where the radial arm is substantially vertical. This gives to the looper a very quick movement into and out of the needle thread loop, or the loops of the needle threads 20 when more than one needle is used, and a relatively long dwell while in the needle thread loop.

Referring more in detail to the drawings, I have shown my improvement as applied to 25 a sewing machine provided with a bed plate 1 and the usual overhanging arm 2. Mounted to reciprocate in the overhanging arm 2 is a needle bar 3 carrying two needles 4 and 5. These needles are set so that the point 30 of the needle 4 is much lower than the point of the needle 5. The material is held on the work support indicated at 6 by means of a presser foot 7, and is fed across the work support by means of a feed dog 8 carried 35 by the feed bar 9 which is given the usual four motions for feeding the material.

Cooperating with the two needles beneath the work support is a single looper 10. This looper 10 is rigidly secured to a looper carrier 11. The looper carrier 11 is provided with a short shaft 12 which is journaled in a bracket 13. Said bracket 13 has spaced bearings 14 and 15 for said shaft. Located on the shaft between the bearings 14 and 15 is 45 a sleeve 16 which is provided with an arm 17. Said arm projects radially from the axis of the shaft and will be hereinafter referred to as a radially extending arm. Mounted on the radially extending arm 17 is a sleeve 18. This sleeve 18 is provided 50 with a laterally extending supporting shaft 19 which in turn is pivotally supported in a bearing 20. This bearing 20 is carried at the upper end of a lever 21. The sleeve 55 is free to oscillate in a vertical plane on the lever 21 and is also free to slide back and forth on the radial arm 17. The lever 21 is vibrated by a link 22 which is connected to the usual needle lever extension. The lever 60 21 is pivoted at 23 on a depending arm 24 carried by the bracket 13. The bracket 13 is mounted on a shaft 25 and secured thereto by set screws 26, 26. The shaft 25 is oscillated in the usual manner from an eccentric 65 on the main shaft and this imparts the lateral

movements to the looper or gives thereto its well known needle avoiding movement. It will be noted that when the looper is moved laterally from its needle avoiding movement, the lever 21 and sleeve 18 also move laterally. 70 In other words, the means which actuates the looper moves bodily with the looper during its lateral movements. When the link 22 is moved endwise it will oscillate the lever 21 and the pivotal point of lever 21 is so disposed relative to the pivotal point of the looper carrier that the sleeve will slide back and forth on the radial arm 17, moving in substantially a horizontal line when the looper is at the forward end of its stroke, and when the lever 21 is at the right hand end of its stroke, as viewed in Fig. 6, the radial arm is substantially vertical. Referring to Fig. 9, the broken line $a-a$ indicates the path of movement of the pivotal support 75 for the sleeve on the lever 21. The sleeve moves from the point x to the point y . As the sleeve moves from the point x to the point z , it is traveling in substantially a horizontal plane, or at least, in that portion of the arc of its travel $a-a$, that will impart little or no oscillating movements to the looper. From the point z to the point y , the sleeve will give the entire oscillating movement to the looper. When moving from the point z to the point y , the looper is retracted from the needle thread loop, and when moving from the point y to the point z , the looper is moved forward into the needle thread loop. Between the points z and y , the center of the shaft 19 carrying the sleeve 20 approaches the axis of the shaft 12 which carries the looper. It will be obvious, therefore, that the looper is given its highest speed of travel for a given angular movement of the lever 21 just as it is about to enter the needle thread loop, and while it is leaving the needle thread loop. This is particularly desirable in a two-needle machine, as it enables the looper to catch both of the needle thread loops. It will therefore be noted that 100 I have provided a means which gives to the looper a very quick travel into and out of the needle loop and without shortening the throw of the looper which travels through an arc of approximately ninety degrees, and at the same time, my improved means gives to the looper an extended dwell while in the needle thread loop. The extent of dwell 105 is substantially during the entire period that the needles are above the work support. This enables both the needles to enter with certainty into the thread triangle, and it enables the looper to pass into both needle thread loops without skipping any stitches. 110 The needles are set at different heights to facilitate the looper taking both needle thread loops.

While I have shown the looper operating mechanism as applied to a looper cooper- 115

ating with two needles, it will be understood of course, that said looper operating mechanism may be used in a single needle machine, and for the purpose of description, I have referred to a single needle thread. In

order that the needles may be properly positioned so that the looper will enter into both needle thread loops, I have provided a needle guard 27 carried by a collar 28 fixed by a set 10 screw 29 to the shaft 25. As this shaft oscillates to bring the looper into position to pass the needles and enter the needle thread loops, the needle guard will also move up into position so as to properly place the needles, if they are for any reason deflected.

My improved looper operating mechanism is especially adapted for a two-needle machine for forming over-edge or covering stitches, and to this end, I have provided 20 a loop forming mechanism for forming the left-hand needle thread into a loop to be entered by the right-hand needle. My improved loop forming mechanism consists of a positioning finger 30 carried by a lever 31

25 pivoted to a bracket 32 mounted on a presser bar 33 which carries the presser foot 7. Said lever 31 is mounted to move in a plane substantially parallel to the line of feed and thus carry the finger 30 from a position in rear of the needles to a position in front of the needles. The lever 31 is so timed that this finger 30 crosses the path of the needle while the needle is up, engages the needle

30 thread of the left hand needle, and moves it forward into the path of the loop forming hook 34. Said loop forming hook 34 is carried by a lever 35. The lever 35 is mounted on a bracket 36 carried at the lower end of the auxiliary presser bar 37 which moves up and down with the main presser bar 33. The pivotal support 38 of the lever 35 is at the left-hand side of the center of the auxiliary presser bar. As a result, the hook 34 moves closer to the right-hand needle than to the

35 left-hand needle, and this enables the hook to engage the left-hand needle thread moved forward by the positioning finger, and form a loop therein and position said loop for the right-hand needle to enter. The lever 35 as well as the lever 31 moves up and down with the presser bars and will therefore, always have a fixed relation to the presser foot in their oscillations. The lever 31 is oscillated by a link 39 which is connected to a collar 40

40 on the needle bar. As the needle bar reciprocates, it will oscillate this lever. The lever 35 is oscillated by means of a link 41 which is connected to an arm 42 attached to a shaft 43 mounted on the overhanging arm and the

45 shaft 43 is in turn oscillated by an eccentric strap 44 cooperating with an eccentric on the main shaft 45. The eccentric strap 44 has an adjustable connection with an arm 46 attached to the shaft 43 so that the throw 50 of the hook may be varied.

My improved stitching mechanism is especially adapted for stitching hat sweats or for doing the type of work disclosed in the patent to Hughes No. 1,257,239, granted February 19, 1918.

Referring to Fig. 14, it will be noted that the machine is provided with a guide 47 which receives the edge of the sweat band that is to pass between the needles, so that one needle will enter the sweat band and the other needle pass over the edge of the sweat band. The swinging yielding guide 48 engages the other edge of the hat sweat and holds it well in the guide 47. The reed passes through a guide 49 which directs the reed into a reed covering strip indicated at C. This reed covering strip passes through a folder 50 which folds the covering strip about the reed and directs the reed and covering strip to the stitching mechanism so that the reed passes between the needles and along the edge of the hat sweat. The covering stitches encircle the reed and the edge of the covering strip, and join the same to the hat sweat.

It is obvious that minor changes in the details of construction and the arrangement of the parts may be made without departing from the spirit of the invention as set forth in the appended claims.

Having thus described the invention, what I claim as new and desire to secure by Letters Patent, is—

1. The combination of a looper, a pivoted looper carrier having an arm projecting substantially radially therefrom, a sleeve slideable on said arm, and means for moving said sleeve bodily in a curved path in a plane at right angles to the pivotal axis of the looper and from a position where the sleeve is substantially vertical to a position where the same is substantially horizontal, so that said sleeve, when the looper is at the forward end of its stroke with the arm horizontal will slide on said arm without imparting any appreciable movement to the looper.

2. The combination of a looper, a pivoted looper carrier for said looper having an arm projecting substantially radially from the carrier, a sleeve slideable on said arm, a pivoted lever carrying said sleeve and mounted upon an axis parallel to and spaced from the pivotal axis of the looper so that said sleeve moves bodily in a curved path from a substantially vertical position to a horizontal position, and slides freely on said arm while said arm is horizontal so as to give an extended dwell to the looper when at the forward end of the looper stroke.

3. The combination of a looper, a pivoted looper carrier for said looper having an arm projecting substantially radially from the carrier, a sleeve slideable on said arm, a pivoted lever carrying said sleeve and mounted upon an axis parallel to and spaced from the pivotal axis of the looper, so that said

- 5 sleeve moves bodily in a curved path from a substantially vertical position to a horizontal position, slides freely on said arm when said arm is horizontal so as to give an extended dwell to the looper when at the forward end of the looper stroke, and means for bodily moving said looper, said lever and said sleeve laterally for giving said looper a needle avoiding movement.
- 10 4. The combination of a looper, a looper carrier, a looper support on which said carrier is pivotally mounted, said looper carrier having a substantially radially extending arm, a sleeve slidable on said arm, and means for moving said sleeve in a curved path for moving said radial arm from a substantially vertical position to a horizontal position, said sleeve sliding on said arm when in horizontal position for giving an extended dwell to the looper at the forward end of the looper stroke.
- 15 5. The combination of a looper, a looper carrier, a looper support on which said carrier is pivotally mounted, said looper carrier having a substantially radially extending arm, a sleeve slidable on said arm, a lever pivotally mounted on said looper support and pivotally supporting said sleeve, means for oscillating said lever, and means for moving said support for giving the looper a needle avoiding movement.
- 20 6. The combination of a looper, a looper carrier, a looper support on which said carrier is pivotally mounted, said looper carrier having a substantially radially extending arm, a sleeve slidable on said arm, a lever pivotally mounted on said looper support and pivotally supporting said sleeve, means for oscillating said lever, and means for moving said support for giving the looper a needle avoiding movement.
- 25 7. The combination of a looper, a looper carrier, a looper support on which said carrier is pivotally mounted, said looper carrier having a substantially radially extending arm, a sleeve slidable on said arm, a lever pivotally mounted on said looper support and pivotally supporting said sleeve, means for oscillating said lever, and means for moving said support for giving the looper a needle avoiding movement.
- 30 8. The combination of a looper, a looper carrier, a looper support having spaced bearings, a looper carrier having a shaft mounted in said spaced bearings, a substantially radially extending arm carried by the shaft between said spaced bearings, a lever mounted on said support, a sleeve pivotally connected to said lever and sliding on said radial arm, said lever being pivot to said looper support at a point at one side of the axis of the shaft of the looper carrier whereby the radial arm is substantially horizontal when the looper is at the forward end of its stroke and the sleeve slides back and forth thereon giving an extended dwell to the looper, and whereby said radially extending arm is substantially vertical when the looper is at the rear end of its stroke, means for oscillating said lever,

and means for oscillating the looper support for giving a lateral or needle avoiding movement to the looper.

8. A sewing machine including in combination, two needles arranged abreast, a looper cooperating with both needles, a pivoted looper carrier, a substantially radially extending arm mounted on said carrier, a sleeve slidable upon said arm, means for supporting and moving said sleeve bodily in a plane at right angles to the pivotal support of the looper, for causing the looper to move quickly out of and into the needle thread loops, said sleeve sliding on said arm when the looper is at the forward end of the looper stroke for giving an extended dwell thereto while in the needle thread loops.

9. The combination of a looper, a looper carrier, means for supporting said looper carrier whereby the same may oscillate about an axis for imparting to the looper its loop taking and loop shedding movements, a member, means for supporting said member whereby the same may be moved back and forth and in a path which approaches the pivotal axis of the looper carrier, and moves away from the same between the ends of its movements, said carrier having means for connection with said member whereby the bodily movement of said member imparts oscillations to said carrier, and devices independent of said looper carrier oscillating means for imparting to the looper needle avoiding movement.

In testimony whereof, I affix my signature. JOSEPH BERGER.
